UNITED STATES PATENT OFFICE

WALTER L. KAUFFMAN, 2d, OF YOUNGSTOWN, OHIO, ASSIGNOR TO LOVELL MANUFACTURING COMPANY, OF ERIE, PENNSYLVANIA, A CORPORATION OF PENNSYLVANIA

DESIGN FOR A WRINGER

Application filed February 17, 1931. Serial No. 38,704. Term of patent 14 years.

To all whom it may concern:

Be it known that I, WALTER L. KAUFFMAN, 2d, a citizen of the United States, residing at Youngstown, in the county of Mahoning and State of Ohio, have invented a new, original, and ornamental Design for a Wringer, of which the following is a specification, reference being had to the accompanying drawing, forming a part thereof.

The figure is a perspective view of a wringer, showing my new design, the front and rear sides of the wringer being substantially the same.

I claim:

The ornamental design for a wringer, as shown and described.

WALTER L. KAUFFMAN, II.
